UNITED STATES PATENT OFFICE

ARTHUR HERMAN ADAMS, OF LA GRANGE, ILLINOIS, ASSIGNOR TO WESTERN ELECTRIC COMPANY, INCORPORATED, OF NEW YORK, N. Y., A CORPORATION OF NEW YORK

METHOD OF AND APPARATUS FOR INSULATING ELECTRICAL CONDUCTORS

Application filed July 25, 1925. Serial No. 46,052.

This invention relates to methods of and apparatus for insulating electrical conductors, and more particularly to methods of and apparatus for baking enamel insulation on wire.

The object of the present invention is to provide an improved and simplified method of and apparatus for speedily insulating electrical conductors with a baked insulating coating.

In order to attain this object in accordance with the features of the invention in one embodiment thereof, a wire continuously passes through a supply of insulating compound, becoming coated therewith, and thence over two spaced metal rollers connected with a source of electrical current so that a current of high frequency passes through the length of the wire between the rollers, the applied coating between each roller and the wire functioning as a dielectric of a condenser. The heating of the ever-changing lengths of portions of the wire by the current passing therethrough bakes the coating from the interior thereof outwardly. In a modified form the rollers are replaced by pairs of suitably spaced condensers between which the coated wire passes.

The method may be practiced by employing an apparatus embodying the invention for baking enamel insulation on the wire in the manner hereinafter described and shown on the accompanying drawings, wherein

Fig. 1 is a diagrammatic view in sectional elevation of the preferred form of the apparatus for baking insulation on the wire;

Fig. 2 is a similar view of a modified form of the apparatus shown in Fig. 1, and

Fig. 3 is a diagrammatic view of the electrical circuit employed with either form of apparatus.

It is believed that the details of the method will be fully understood from a description of the apparatus by which it may be practiced. Fig. 1 of the drawing illustrates the preferred form of apparatus, which comprises an insulating compound container 10 which has therein a quantity of insulating compound 11, preferably in liquid form of any suitable character which may be baked

or otherwise hardened by the application of heat, and which may be supplied or replenished in any suitable manner from a supply so as to keep the compound at a uniform level in the container. Positioned adjacent to and supported in any well known manner in a vertical position above and at one side of the insulating compound container 10 is a heat retaining chamber or tube 12. This heat retaining chamber or tube may be made of wood or asbestos board and lined with metal for the purpose of retaining and holding the heat during the process of baking the insulating coating upon the wire. In determining the proper length of this tube the factors which must be taken into consideration are the size of the wire to be insulated and the speed at which the wire travels through this chamber. The upper end of the tube or heat retaining chamber 12 is purposely tapered inwardly as shown at 13 for the purpose of retarding the escape of heat, but at the same time providing an opening of sufficient size at the upper end thereof to permit the vapor resulting from the baking of the insulating compound on the wire to escape.

Mounted within the compound container 10 on suitable bearings and in a position to be partially submerged in the insulating compound 11 is a sheave 14. This sheave is provided with a suitable collar 15 formed integrally therewith for a purpose hereinafter set forth. Mounted in any suitable position adjacent the heating chamber on a suitable spindle is a wire supply spool or reel 16 from which a wire 17 is fed over a supply guide roller 18. The guiding pulley or supply guide roller 18 is positioned vertically over the sheave 14 so as to direct the wire in a vertical line downwardly. Positioned below the supply guide roller 18 and at one side thereof and mounted on a suitable bearing is a soft iron idler pulley 19 for the purpose hereinafter set forth. The wire 17 is led from the supply spool or reel 16 over the supply guide roller or pulley 18 downwardly around the sheave 14 and upwardly in a vertical direction through the longitudinal center of the heat retaining tube or chamber 12 where it is trained around an 100

upper sheave 20 and thence vertically in a downward direction around the soft iron idler pulley 19. At this point the returning coated wire is wound around several times for the purpose of making an impedance which prevents the short circuiting of the going up wire or that portion of the wire being baked in the heat retaining chamber as will hereinafter be more fully described.

10 The wire is led from the iron idler pulley 19 about another sheave identical with that shown at 14 and may again receive a second coat of insulating compound and pass through a second heat retaining chamber upwardly over a pulley or sheave similar to that shown at 20, from where it may again be repeated and several coats of insulating compound thus applied according to the requirements, after which it is led to a receiving reel or spool 21, which may be operatively driven in any well known manner to wind the insulated wire thereon.

One of the important features of the present process of and apparatus for baking insulation on the wire consists of passing an electrical current successively through portions of a continuously moving wire and thereby heating the wire over this portion in such a manner that the insulation is baked thereon during the time it is traveling through the heat retaining chamber.

Another important feature is that the solvents and distillable portions of the compound or enamel or varnish are driven off from the inside of the coating outwardly, and the outer surface of the coating remains fluid longer than the inner portion. This obviates the microscopic pores that might sometimes occur when the heating is done from the outside inward, by reason of the outer surface partially "drying" first and being ruptured by vapors evolved from the inner portion of the compound layer.

The apparatus for accomplishing or causing the electrical current to pass through this ever-changing portion or length of the wire comprises an oscillator or other source of high frequency current of relatively low voltage as shown diagrammatically at 22, which is connected by suitable wiring 23 and a spring pressed contact member 24 with a collar 25 formed integrally with the upper sheave or pulley 20. The other terminal is connected by a wire 26 and spring contact member 27 which contacts with the collar 15 of the sheave or pulley 14. It will, of course, be understood that the coating of insulation between the rollers and the wire forms the dielectric of a condenser at both the upper and lower ends of the length of wire passing from the sheave 14 to the sheave 20, and in order to prevent the returning portion of the coated wire from short circuiting the portion being baked within the heat retaining chamber or tube 12 a high retarda-

tion impedance to the high frequency alternating current is introduced in this returning coated portion by passing the returning portion several times around the soft iron idler 19, as previously described. The circuit thus established is shown diagrammatically in Fig. 3.

It should be understood that the frequency used should be so high that the impedance of the two condensers, formed by the wire passing over the sheaves 20 and 14, will be negligible in relation to the resistance of that portion of the wire it is desired to heat. This is necessary both because these condensers are quite variable and because otherwise the circuit would be very inefficient, in that energy would be dissipated elsewhere than where desired.

From the above description it will be seen that as the moving wire is led from the supply spool into the insulating compound 11, where it is coated with the same, the ever-changing portions of equal length successively extending between the sheaves 14 and 20 are being heated by the high frequency electrical current passing through this portion as part of the circuit, and that the heat retaining chamber or tube 12 retains the heat in a manner to insure complete baking or hardening of the insulation covering.

In the modified form shown in Fig. 2 the manner in which the wire is led from the supply reel 16 to the receiving reel 21 is substantially identical with that shown in Fig. 1, the only difference being that adjacent the upper and lower ends of the heat retaining chamber or tube 12 are positioned two electrodes or condenser plates 28 and 29 which are operatively associated with the coated wire for conveying electrical current to that portion of the coated wire extending between these plates. The coated wire is guided at the upper end of the heat retaining chamber or tube 12 by a glass or nickel roller 30. The roller 30 maintains the wire in a relatively fixed vertical line during its movement through the heat retaining chamber. The statements given above in connection with the description of the apparatus shown in Fig. 1 regarding the circuit, the character of the current employed, and the introduction of impedance to prevent short circuiting of one portion of the wire by another portion thereof are equally applicable to the apparatus shown in Fig. 2.

While in the above specification I have described specific embodiment which my invention may assume in practice, it will, of course, be understood that various further modifications may be made without departing from the spirit and scope of the invention as expressed in the following claims.

What is claimed is:

1. In an apparatus for insulating an electrical conductor, means for applying a coat-

ing of insulating material to the conductor, a source of high frequency electrical current, spaced terminals therefor positioned adjacent the coated conductor for passing high frequency electrical current through and thereby heating the portion of the conductor between the terminals to bake the coating thereon, and means to cause a relative movement between the terminals and the conductor to continuously change the portion of the conductor being heated to thereby continuously bake the coating thereon.

2. The method of baking a coating on an electrical conductor, which consists in generating a high frequency electrical current outside of said wire, passing said current through the coating and through a selected portion of the conductor and thereby heating the portion to bake the coating.

3. The method of baking a coating on an electrical conductor, which consists in positioning adjacent the conductor at spaced points, terminals of a source of high frequency electrical current to cause an electrical current to pass through the portions of the conductor between the points, thereby heating the portions to bake the coating.

4. The method of baking a coating on an electrical conductor, which consists in employing the coating as a dielectric in a condenser for passing a high frequency current through the conductor, and thereby heating the conductor to bake the coating.

5. The method of baking a coating applied to an electrical conductor, which consists in moving the conductor along a predetermined path, and simultaneously passing electrical heating current through adjacent ever-changing equal lengths of the conductor.

6. The method of baking a coating on an electrical conductor, which consists in passing an alternating electrical current through adjacent ever-changing equal lengths of the conductor, thereby successively heating the lengths to bake the coating.

7. In an apparatus for insulating an electrical conductor, means including guide members positioned adjacent the conductor at spaced points along its length for applying a coating of insulating material to the conductor, and means employing the guide members as terminals and employing the applied coating as a dielectric in a condenser for passing a high frequency electrical heating current through the coated conductor.

8. In an apparatus for baking a coating applied to a base, means for moving the coated base along a predetermined path, and means employing the coating as a dielectric in a condenser for passing a high frequency electrical heating current through the base during such movement.

9. In an apparatus for baking a coating

applied to a base, means for moving the coated base along a predetermined path, and means employing the coating as a dielectric in a condenser for passing a high frequency electrical heating current through ever-changing equal lengths of the base during such movement.

10. In an apparatus for baking a coating applied to a base, means including spaced guide members for moving the coated base along a predetermined path, means employing the guide members as terminals and employing the applied coating as a dielectric in a condenser for passing a high frequency electrical heating current through ever-changing equal lengths of the base during such movement, and means for substantially confining the heating current to said ever-changing lengths.

11. In an apparatus for baking a coating applied to a base, spaced guide members positioned adjacent the coated base, means for causing a relative movement between the coated base and the guide members, and means employing the guide members as terminals and employing the applied coating as a dielectric in a condenser for passing a high frequency electrical heating current through ever-changing equal lengths of the base during such movement.

In witness whereof, I hereunto subscribe my name this 14th day of July, A. D. 1925.

ARTHUR HERMAN ADAMS.
